[57] CLAIM

The ornamental design for a locking element to be employed with a chain or tether for attaching ski poles to skis, as shown and described.

DESCRIPTION

FIG. 1 is a side perspective view of the locking element to be employed with a chain or tether for attaching ski poles to skis embodying the design of the present invention;

FIG. 2 is a front end elevational view thereof;

FIG. 3 is a rear end elevational view thereof;

FIG. 4 is a side elevational view thereof of the side

opposite to the side shown in FIG. 1; and,

FIG. 5 is a top plan view thereof, the bottom view being

identical to the top shown in FIG. 5.

FIG. 1

FIG. 2

FIG. 3

FIG. 4

FIG. 5
